GARBAGE CAN SAFETY LOCK

Andrew C. Frey, Jackson, Mich.

Application September 11, 1951, Serial No. 246,037

2 Claims. (Cl. 220—55.7)

1

The present invention relates to a garbage can safety lock and it consists in the combinations, constructions and arrangements of parts herein described and claimed.

Generally there is provided a garbage can safety lock which may be quickly and easily attached to the conventional garbage can to thereby maintain the cover thereof upon such can despite the manipulations of dogs, cats or the weather.

It is an object of the invention to provide a device of the character set forth which is simple in construction, inexpensive to manufacture and yet effective and efficient in use.

Another object of the invention is to provide a novel garbage can lock having simple means for attaching and detaching the same from a conventional garbage can.

Other and further objects of the invention will become apparent from a reading of the following specification taken in conjunction with the drawing, in which:

Figure 1 is a side elevational view of an embodiment of the invention shown attached to a conventional garbage can,

Figure 2 is a side elevational view of a safety hook forming a part of the invention,

Figure 3 is an exploded elevational view of a spring forming part of the invention, and

Figure 4 is an elevational view of a permanent fastening device which forms a part of the invention.

Referring more particularly to the drawing, there is shown therein a device of the character set forth which consists of a permanent fastening member generally indicated at 10 and which is substantially triangular in form and which is formed of a single piece of wire whose free ends form a gap 11 in the one side of the triangular structure, the free ends being indicated at 12.

To the apex portion of the fastener 10 there is connected one end of a tension spring 13 the other end being connected to an eye 14 of a safety lock generally indicated at 15. The lock 15 is formed of a single piece of wire having the eye 14 at one end and a hook 16 at the other end while midway of the lock 15 there is provided an integrally formed outwardly extending handle 17.

There is also illustrated in Figure 1 of the drawing a garbage can 18 provided with a bail 19 mounted in conventional bail ears 20. A cover 21 is provided for the can 18 and has centrally mounted atop thereof a handle 22.

In operation two of the devices forming the present invention are utilized and each is at-

2

tached to the garbage can by extending the member 10 through the handle 22 and thereafter bringing the ends 12 of the member 10 together beneath the handle 22 to securely hold the same upon such handle. The spring 13 interconnects the member 10 and the lock 15 by being engaged with the eye 14 of the lock 15. The hook 16 of the lock structure 15 extends beneath the ends of the bail 19 adjacent the bail ears 20 and it will be apparent that when it is desired to engage or disengage the hook 16 from its respective portion of the bail 19, it is only necessary to manipulate the handle 17 thereof either upwardly or downwardly to engage or disengage the hook 16 as aforesaid. When the devices are mounted upon the garbage can structure as illustrated in Figure 1, it will be seen that the springs act to securely maintain the cover 21 upon the can 18 to thus foil the attempts of dogs, cats and other animals or the actions of the weather to remove the cover 21 from such can 18.

While but one form of the invention has been shown and described herein, it will be readily apparent to those skilled in the art that many minor modifications may be made without departing from the spirit of the invention or the scope of the appended claims.

What is claimed is:

1. A safety device for garbage cans and the like comprising in combination with a garbage can provided with a cover, a handle centrally affixed to said cover, a pair of bail ears disposed at opposite sides of said can near the top edge thereof and a bail adapted to engage in said ears, a pair of complementary fastening members triangular in form and having a gap in one side thereof, said members adapted to removably engage with said handle by means of said gap and having the apex opposite the said gap positioned outwardly, a pair of safety locks having their end portions bent downwardly in hook-like form and an integrally formed outwardly extending handle portion midway of the length thereof, means for connecting the said fastening members with the said lock means, and means for connecting said lock means with said bail.

2. A safety device for garbage cans or the like as described in the foregoing claim 1, wherein said means for connecting the said fastening means with the said lock means comprises a complementary pair of yieldable members each adapted to have one end thereof removably attached to the apex of said fastening member and the opposite end removably attached to the upper end of said locking member, and the free

3

end of the said locking member removably attached in the eye of the said bail end.

ANDREW C. FREY.
